UNITED STATES PATENT OFFICE.

JOHN A. LIEB, OF NEWARK, NEW JERSEY, ASSIGNOR TO WHEELER,
PARSONS & HAYES, OF NEW YORK, N. Y.

DESIGN FOR AN ORNAMENTAL CHAIN.

SPECIFICATION forming part of Design No. 11,855, dated July 6, 1880.

Application filed May 31, 1880. Term of patent 7 years.

To all whom it may concern:

Be it known that I, JOHN A. LIEB, of the city of Newark, in the county of Essex and State of New Jersey, have originated and produced a new Design for Jewelry-Chains, of which the following is a specification, reference being had to the accompanying drawings, forming part thereof.

Figure 1 represents a side view of a piece 10 of chain embodying my design. Fig. 2 represents an end view thereof. Fig. 3 represents a face view of one of the links of which the chain is composed, and Fig. 4 represents an edge view of such link.

15 Similar letters of reference designate corresponding parts in all the figures.

The form of the links A, from which the chain is made, is shown clearly in Fig. 3. The link is in the form of two ellipses, a, having 20 their minor axes in line with each other and joined for about half their length, as shown at b, leaving an opening or cleft, c, between them, extending about half their length. In each ellipse is an elliptical slot or aperture, d, and 25 the link is bent between the two ellipses so that they are at an angle to each other, as shown in Fig. 4.

When joined together to form a chain the links A are arranged in pairs, the links of

each pair being arranged obliquely to each other in a direction lengthwise of the chain, and the alternate pairs of links being arranged at approximately a right angle to the intermediate pairs, thus forming a chain which is approximately quadrangular in transverse section.

The several links are secured by inserting the elliptical portions of each pair of links through the slots or apertures d of the adjacent pair of links.

What I claim, and desire to secure by Letters Patent, is—

1. The design for a chain-link, A, herein shown and described, consisting of the two ellipses a, with slots or apertures d, joined at 45 b, and having a cleft, c, between them.

2. The design for a chain, consisting of the pairs of links A, of the form of two ellipses, a, having slots or apertures d, joined at b, and having a cleft, c, between them, the said links 50 of alternate pairs being at approximately a right angle to the links of intermediate pairs, as herein shown and described.

JOHN A. LIEB.
